UNITED STATES PATENT OFFICE.

THOMAS McMANUS AND GEORGE K. SMART, OF ATCHISON, KANSAS.

COMBINED LIFTING-JACK AND TRACK-LINER.

SPECIFICATION forming part of Letters Patent No. 541,002, dated June 11, 1895.

Application filed January 22, 1895. Serial No. 535,778. (No model.)

To all whom it may concern:

Be it known that we, THOMAS McMANUS and GEORGE K. SMART, both of Atchison, in the county of Atchison and State of Kansas, 5 have invented a new and Improved Combined Lifting-Jack and Track-Liner, of which the following is a full, clear, and exact description.

The invention relates to railroad implements; and its object is to provide a new and combined lifting jack and track liner, which is comparatively simple, light, economical and durable in construction, and arranged for conveniently and rapidly raising the track 15 or shifting the same sidewise, without injury the track-bed or track.

The invention consists principally of a horizontal base or lining bar, a hollow post or bar with or without roller bearings fitted to slide 20 thereon, and a lifting bar fitted to slide in the post and adapted to support the rail.

The invention also consists of certain parts and details and combinations of the same, as will be fully described hereinafter and then 25 pointed out in the claims.

Reference is to be had to the accompanying drawings, forming a part of this specification, in which similar letters of reference indicate corresponding parts in all the figures.

30 Figure 1 is a perspective view of the improvement as applied, showing the employment of two jacks and track-liners. Fig. 2 is a sectional perspective view of the improvement with the device for lifting the post omitted, and also the lifting-lever. Fig. 3 is a perspective view of the post-shifting device. Fig. 4 is a sectional side elevation of the same, and Fig. 5 is a perspective view of the reciprocating ram.

40 The improved lifting jack and track liner is provided with a base or lining bar A, preferably made of metal and T-shaped in form, and having the vertical member A', provided with a base plate B, for supporting the lining 45 bar on the track bed.

A horizontal member A² forms guideways for the lower sliding part C' of a post C, likewise made of metal and hollow, and fitted to slide on the horizontal member A² of the lining bar. Suitable roller bearings may be employed between the post and member A². In 50 this hollow post C is fitted to slide vertically,

the lifting bar D, also made hollow and square in cross section, one side being provided with a foot D', projecting through a slot C², formed 55 in the adjacent side of the post C. This projecting foot D' is adapted to support the base of a rail to shift or lift the latter, as herein-after more fully described.

On the inside of the lifting bar D, on the 60 side carrying the foot D', are ratchet teeth D², engaged by a spring-pressed pawl E, set with its pivot end in a recess F', formed in the lifting ram F, fitted to slide vertically within the lifting bar D, as is plainly indicated in Fig. 2. In the upper end of this ram F is arranged a transverse opening F², adapted to be engaged by a transverse bearing G' on the end of a lever G having its fulcrum G² in bearings C³, formed integral with the upper 70 end of the post C. Now, it will be seen that by the operator swinging the lever G up and down, a reciprocating motion is given to the ram F, so that the pawl E, carried by the said ram and engaging the teeth D², lifts the lifting bar D within the post C, so as to raise the rail supported on the foot D'.

In order to hold the lifting bar in position after it is raised, on the upward sliding movement of the ram F, a supporting pawl H is 80 provided having its fulcrum H' in a seat C⁴ forming part of the post C, and arranged at the lower inner side thereof, as plainly indicated in the drawings.

The supporting pawl H is pivotally connected at its upper end with a rod H², extending through the open side of the lifting bar D, and through a slot on the inner side of the post C, the outer end of this rod H² being pivotally connected with a cam I, having a 85 handle I', and adapted to abut against the outer face of the inner side of the post C, so that the operator, on moving the handle I' upward, exerts a pull on the rod H², to lift the supporting pawl H out of contact with the teeth D² to permit the lifting bar D to descend, when it is desired to lower the rail and track. A rod may be employed to connect the handle I' with the lever G for pulling the device out of gear to release the supporting 90 pawl.

The pawl H is provided with an upper extension H³, adapted to engage the lifting pawl E, so that when the rod H² is pulled outward 100

and the pawl H moves out of engagement with the teeth D², then the extension H³ at the same time engages the pawl E and swings the latter out of engagement with the teeth D².

5 In order to hold the rail in position on the foot D' of the lifting bar, a hook J is pivoted on the front of the post C, as indicated at the right in Fig. 1.

In order to shift the post C on the lining 10 bar A to move the rails and track ties sidewise, the following device is provided, particular reference being had to Figs. 3 and 4.

A plate K, extending over the inner part of the horizontal member A², is adapted to be 15 fastened by a pin K', to the lower end C' of the post C. The outer end of this plate K is formed with a forked head K², carrying a transverse pivot pin K³, on which are held guideways I, engaging the side edges of the 20 horizontal member A² of the lining bar A, to hold the plate K in proper position on the member A², but to permit a sliding movement thereon.

On the pivot pin K³ is fulcrumed a lever N 25 under the control of the operator, and carrying two pawls O and P, located one above the other, and each being pressed on at its pivoted end by a spring O' or P' respectively. The pawls O and P are fulcrumed in the head 30 N' of the lever N, as is plainly shown in Fig. 4, and the pawls are of different lengths and are adapted to engage with their free ends, teeth A³ formed in the upper surface of the horizontal member A².

25 The longer and uppermost pawl O is provided at its pivot end, with an upwardly extending handle O², adapted to be taken hold of by the operator, to throw the said pawl out of mesh with the teeth A³ whenever it is desired. The lower and shorter pawl P is connected by a link P² with a hook P³, adapted to be hooked onto the projection N² of the lever N, to throw the pawl P out of engagement with the teeth A³.

45 In the front end of the plate K is arranged a catch K⁴, adapted to be moved in and out of engagement with the teeth A³ by a handle K⁵, connected with the catch, and having its bearing in the plate K, as indicated in Fig. 3. The catch K⁴ is moved out of engagement with the teeth A³ whenever it is desired to use both pawls O and P at the same time. When it is desired to use but the pawl P then the catch K⁴ is moved in engagement with the teeth A³ for the purpose of holding the bar in position while taking the backward movement with the pawl P.

For very heavy tracks, it is advisable to employ two lifting jacks and track liners, as 60 indicated in Fig. 1, the said jacks being connected with each other by a chain Q, hooked on a hook R, secured on the post C of the jack on one side, the other end of the chain being connected with the pivot pin K³ of the 65 plate K, fastened to the post C of the other track liner. Now, it will be seen that in manipulating the lever N, that is, in moving it

up or down, the pawl O or P, or both, imparts a sliding motion to the plate K, so as to shift the post C and the rail supported thereon 70 sidewise, until the rails are in the proper position.

It will be seen that by the construction described, a single machine only, is required to lift the rails and ties by moving the same 75 sidewise until the proper position is obtained, it being understood that the lining bar or base A is placed between two adjacent ties on the railroad bed, and the levers G and N are manipulated as set forth, to either raise the rails 80 and ties, or to shift the same sidewise.

When one lining bar and jack is used the chain is provided with clamps to connect the opposite rails to said lining bar. These clamps by being placed close together give greatest 85 length of chain when placing the shorter ends farther apart.

Having thus fully described our invention, we claim as new and desire to secure by Letters Patent—

1. A device of the class described, comprising a base or lining bar, a post fitted to slide thereon, and a lifting bar fitted to slide in the post and adapted to support the rail, substantially as shown and described. 90

2. A device of the class described, comprising a base or lining bar, a post fitted to slide thereon, a lifting bar fitted to slide in the post and adapted to support the rail, and means for imparting a sliding motion to the said 100 post on the said lining bar, as set forth.

3. A device of the class described, comprising two lining bars, posts fitted to slide thereon, a shifting device for moving one of the posts on its lining bar, and a connection between the other post and the shifting device, substantially as shown and described. 105

4. A device of the class described, comprising a lifting jack provided with a hollow post, a hollow lifting bar fitted to slide therein and 110 having a toothed surface, said bar being provided with a foot projecting to the outside of the post, a ram having a reciprocating motion in the hollow of the said lifting bar, a spring-pressed pawl supported on the said ram, and 115 engaging the teeth of the lifting bar and a supporting pawl held on the said post and engaging the teeth of said lifting bar, substantially as shown and described.

5. A device of the class described, comprising a lifting jack provided with a hollow post, a hollow lifting bar having a toothed surface fitted to slide thereon and provided with a foot projecting to the outside of the post, a ram having a reciprocating motion in the hollow 125 of said lifting bar, a spring-pressed pawl supported on the said ram, a supporting pawl held on the said post said pawls engaging the teeth of the said lifting bar, and a lever fulcrumed on the said post and engaging the said 130 ram to impart a reciprocating motion to the latter, substantially as shown and described.

6. A device of the class described, provided with a lifting jack provided with a hollow post,

- lifting bar fitted to slide thereon and provided with a foot projecting to the outside of the post, a ram having a reciprocating motion in the said lifting bar, a spring-pressed pawl supported on the said ram, a supporting pawl held on the said post and engaging the said lifting bar, and means, substantially as described, for moving the said supporting pawl out of engagement with the said lifting bar, 10 a lifting pawl engaging the lifting bar, the said supporting pawl being adapted to move the lifting pawl out of engagement with the lifting bar, substantially as shown and described.
- 15 7. A device of the class described, comprising a toothed lining bar, a post fitted to slide thereon, a lifting bar fitted to slide in the post and adapted to support the rail, and a shifting device comprising a plate adapted to be

fastened to the said post, and a lever fulcrumed on the said plate, and provided with one or more pawls engaging the teeth of the said lining bar, substantially as shown and described.

8. A device of the class described, provided with a shifting device comprising a plate having a forked head and supporting a pivot pin, a lever fulcrumed on the said pivot pin, and two pawls fulcrumed on the head of the said lever, one of the said pawls being provided with a supporting device to support the pawl on the lever, substantially as shown and described.
